A. P. TESELSKY

PLIERS

Filed June 14, 1921

Inventor

A. P. Teselsky.

By
O. Randolph Jr.,
Attorney

UNITED STATES PATENT OFFICE.

ALEX P. TESELSKY, OF RUSO, NORTH DAKOTA.

PLIERS.

Application filed June 14, 1921. Serial No. 477,416.

To all whom it may concern:

Be it known that I, ALEX P. TESELSKY, a citizen of the United States, residing at Russo, in the county of McLean and State 5 of North Dakota, have invented certain new and useful Improvements in Pliers; and I do hereby declare the following to be a full, clear, and exact description of the invention, such as will enable others skilled in 10 the art to which it appertains to make and use the same.

The invention relates to tools of the pliers type and aims to provide an implement of this character embodying a third jaw 15 disposed to coact with the usual jaws of the pliers to prevent the article gripped from slipping.

The invention furthermore provides a tool 20 of the pliers type with shear blades for cutting sheet metal, one of the blades being adjustable whereby to bring a sharp portion in operative position when the active portion has become dull.

Other objects and advantages will be apparent and suggest themselves as the nature 25 of the invention is understood.

While the drawing illustrates an embodiment of the invention it is to be understood that in adapting the same to meet different 30 conditions and requirements, various changes in the form proportion and minor details of construction may be resorted to without departing from the nature of the invention.

35 Referring to the accompanying drawing forming a part of the specification,

Figure 1 is a plan view of pliers embodying the invention.

Figure 2 is a view similar to Figure 1 as 40 seen from the reverse side.

Figure 3 is a section on the line 3—3 of Figure 1, and

Figure 4 is a section on the line 4—4 of Figure 2.

45 Corresponding and like parts are referred to in the following description and designated in the several views of the drawing by like reference characters.

The tool comprises two levers or members 50 which cross near one end and are pivotally connected at the point of crossing. One of the lever members is designated by the numeral 1 and has a jaw 2. The companion lever member is designated by the numeral 3 and embodies a jaw 4. To increase the 55 range of usefulness of the tool one of the

members terminates in a claw 5 and the other in a screw driver point 6. A third jaw 7 is adjustably connected to the tool by means of a shank 8 which preferably curves in its length whereby the jaw 7 is adjustable on a curved line. The members and shank 8 are connected by means of a pivot 9, the latter serving to secure the third jaw 7 in the adjusted position. The shank 8 has a slot 10 which is enlarged at points in its length as indicated at 11 to receive the pivot fastening 9 whereby to hold the shank 8 and jaw 7 in the required adjusted position. That portion of the pivot fastening 70 9 passing through the slot 10 is flattened upon opposite sides to provide for adjustment of the jaw 7 when the parts are moved to a position to bring the flattened portions of the pivot 9 in line with the slot 10. This 75 position is assumed when the members 1 and 3 are open to the limit of their movement. After the jaw 7 has been adjusted to the required position it is made secure by partly closing the members which causes 80 the flattened portion of the pivot 9 to enter the selected enlargement 11 of the slot 10 whereby movement of the shank 8 and jaw 7 is prevented. The forward portion of the member 3 is cut away upon its outer side 85 to receive the shank 8. A rib or flange 12 is formed along the outer edge of the cut away portion of the member which engages the outer edge of the shank 8, which is thereby held in position in connection with the 90 pivot fastening 9. The inner edge of the shank 8 is beveled to form a cutting edge 13 which coacts with a corresponding cutting edge along the inner side of the jaw 2. A portion of the jaw 2 is cut away as indicated at 14 and the same is beveled to provide 95 the cutting edge to coact with the cutting edge 13 whereby the tool is adapted to be used as metal shears in cutting for sheet metal.

The work ends of the jaws 2 and 4, respectively, have projections indicated at 15 and 17 while a corresponding projection at 16 is provided on the jaw 7 in order to provide effective gripping surfaces. The projections 14, 15 and 16 are substantially in the same plane whereby provision is had for receiving the flange or knurled edge of oil cups to provide clearance therefor thereby enabling the body portion to be firmly and securely gripped by the jaws. The jaws 4 and 7 are toothed to prevent slipping. The 105 110

third jaw 7 may be adjusted so as to occupy a position opposite the jaws 2 and 4 when the cup or other article is gripped by the tool. The third jaw 7 performs the function of a holder or retainer to prevent slipping when closing the jaws 2 and 4 upon the article to be gripped. The shank 8 constitutes a shear blade or cutting member and is adjustable to admit of bringing a sharp portion of the cutting edge 13 in operative position when required.

Having thus described the invention, what I claim is:—

1. A tool of the class described having relatively movable lever members providing coacting jaws, a shank having a coacting jaw in spaced relation to said jaws and arranged to grip an object simultaneously therewith.
2. A tool of the class described having relatively movable lever members providing coacting jaws, a shank extensibly mounted on one of said jaws and having a jaw in spaced relation to the first mentioned jaws and arranged to grip an object simultaneously with the first mentioned jaws.
3. A tool of the class described having relatively movable lever members providing coacting jaws, a shank having a coacting jaw in spaced relation to said jaws and arranged to grip an object simultaneously therewith, a pivot element for the said members, the shank having a slot through which the pivot element passes, and said shank and slot constituting the means to extensibly mount the shank.
4. A tool of the class described having relatively movable lever members, a shank, said members and shank having coacting jaws, a pivot element for the members and interengaging means between said pivot member and shank to adjustably secure the shank in place and engageable and disengageable according to the position of one lever member relatively to the other lever member.
5. A tool of the class described having relatively movable lever members, a shank, said members and shank providing coacting jaws, a fastening extending from one of the lever members, the shank having a slot into which said fastening extends, said slot being elongated and provided with enlargements, and said fastening being movable and provided with means to engage and disengage the enlargement to provide for adjustment of the shank.
6. A tool of the class described having relatively movable lever members, a shank, said members and shank providing coacting jaws, a fastening extending from one of the

lever members, the shank having a slot into which said fastening extends, said slot being movable and provided with means to engage and disengage the enlargement to provide for adjustment of the shank, said fastening constituting the pivot for the lever members and one of the lever members having a flange in abutment with the shank and to coact with the fastenings in securing the shank in different adjustments.

7. A tool of the pliers type comprising in addition to the usual two jaws a third jaw disposed forwardly of the usual jaws and adapted to cooperate therewith to retain an article and prevent slipping.

8. A tool of the pliers type embodying in addition to the usual two jaws a third jaw having adjustable connection with the tool and disposed forwardly and opposite the two ordinary jaws for cooperation therewith in the capacity of the holder or retainer.

9. A tool of the pliers type comprising two members pivotally connected and a third jaw having a shank retained in position by the pivot fastening connecting the two members of the tool.

10. A tool of the pliers type comprising two members pivotally connected, a third jaw having a shank longitudinally slotted to receive the pivot fastening of the tool and adjustable thereon and retained in the adjusted position thereby.

11. A tool of the pliers type comprising two members pivotally connected, a third jaw having a shank seated upon one of the members and retained in position by the pivot fastening.

12. A tool of the pliers type comprising pivoted lever members, a pivot fastening therefor having opposite sides flattened, a third jaw having a shank longitudinally slotted and having the slot enlarged at intervals, the flattened portions of the pivot fastening entering the slot of the shank and cooperating with the enlargements thereof to retain the third jaw in the required adjusted position.

13. A tool of the character specified comprising co-acting lever members each having a jaw, a third jaw adjustably connected with the tool and cooperating with said jaws thereof, the several jaws having their gripping surfaces substantially in the same plane to facilitate gripping an article.

In testimony whereof I affix my signature in presence of two witnesses.

ALEX P. TESELSKY.
